(57) **CLAIM**

The ornamental design for a charging handle for a firearm, as shown and described.

DESCRIPTION

FIG. 1 is a front perspective view of the charging handle for a firearm of the present invention;

FIG. 2 is a second front perspective view of the invention of FIG. 1;

FIG. 3 is a back perspective view of the invention of FIG. 1;

FIG. 4 is a bottom plan view of the invention of FIG. 1; FIG. 5 is a top plan view in elevation of the invention of FIG. 1;

FIG. 6 is a side view of the invention of FIG. 1, as seen from the right side of FIG. 5;

FIG. 7 is a side view of the invention of FIG. 1, as seen from the left side of FIG. 5;

FIG. 8 is a side view of the invention of FIG. 1, as seen from the top side of FIG. 5; and,

FIG. 9 is a side view of the invention of FIG. 1, as seen from the bottom side of FIG. 5.

The broken lines represent portions of the charging handle for a firearm that form no part of the claimed design.
